(57) **CLAIM**

The ornamental design for a golf club grip, as shown and described.

DESCRIPTION

FIG. 1 is a perspective view of the golf club grip;

FIG. 2 is a top view thereof;

FIG. 3 is a right side view thereof;

FIG. 4 is a bottom view thereof;

FIG. 5 is a left side view thereof;

FIG. 6 is an end view thereof; and,

FIG. 7 is an end view thereof opposite FIG. 6.

The broken lines shown in the drawings form no part of the claimed design.
